UNITED STATES PATENT OFFICE.

I. J. SAUNDERS, OF SPARTA, GEORGIA.

IMPROVEMENT IN GUANO-SPREADERS.

Specification forming part of Letters Patent No. 31,409, dated February 12, 1861.

To all whom it may concern:

Be it known that I, IRVIN J. SAUNDERS, of Sparta, in the county of Hancock and State of Georgia, have invented a new and useful Improvement in Guano-Spreaders; and I do hereby declare that the following is a full, clear, and exact description thereof, reference being had to the accompanying drawings, making part of this specification, in which—

Figure 1 is a vertical longitudinal section of the machine through the plane indicated by the red line *v* in Fig. 2. Fig. 2 is a plan or top view of the same.

Similar letters of reference indicate corresponding parts in both figures.

This invention consists in the combination of two hoppers, a discharge governor or slide, and a cam-wheel and its driving-pulley, with an ordinary wheelbarrow-frame, the same constituting a very simple and efficient apparatus for spreading guano and other pulverized fertilizers by hand.

To enable those skilled in the art to make and use my invention, I will proceed to describe its construction and operation, having reference to the drawings.

I use the ordinary wheelbarrow, which consists of the wheel *w*, its shaft *s'*, the handles *h*, cross-bars *f* and *g*, and the standard *n*, with their circular braces or supports *y*.

The primary hopper *A* is suspended in the rectangular space between the handle *h* and the cross-bars *f* and *g*, and is nailed to the former. Its sides converge toward the bottom and the secondary or vibrating hopper *B* incloses its mouth and is pivoted to it eccentrically to itself, so that its gravity shall cause its front side to rest against the cam-wheel *c*. Said hopper *B* is provided with a sort of flat tube, *a'*, which projects obliquely from the rear side and extends across its full width, as shown by the dotted lines in Fig. 2, so that

the slide *s*, with which the said tube *a'* is provided, shall entirely close the mouth or discharge of the hoppers when necessary by sliding it clear in, and the quantity spread may be increased or diminished, as desired, by withdrawing the slide *s* or shoving it in, and the adjustment in either case is preserved by the key *e'*, (seen in Fig. 1,) which passes through the tube and one of the several orifices in the slide *s*. The shaft of the cam-wheel *c* and the pulley *a* is hung in the standard *n*, extending from side to side in front of the hoppers, as shown by dotted lines in Fig. 2. The cam-wheel *c* and pulley *a* are driven by the band *b* from the pulley *d*, which is rigidly fixed to the axle *s'* of the driving-wheel *w*. This spreading apparatus may be applied to any ordinary wheelbarrow by suspending the hopper between the handles *h* and nailing it to them, boring a hole in both standards *n* to receive the journals of the shaft of the pulley *a* and the cam *c*, and affixing a pulley, *d*, to the shaft *s'* of the wheel.

The hopper *A* is filled with guano, the slide *s* withdrawn so as to spread the desired quantity, where it is secured by the key *e'*, and as the operator propels the machine the band *b* revolves the cam-wheel *c*, which produces a constant vibration of the hopper *B* and a continuous discharge of the fertilizer.

What I claim as new, and desire to secure by Letters Patent, is—

The combination of two hoppers, *A* and *B*, slide *s*, cam-wheel *c*, and its driving-pulley *a*, with an ordinary wheelbarrow-frame, all the parts being constructed, arranged, and operating in the manner and for the purpose herein set forth.

IRVIN J. SAUNDERS.
